Primary Examiner — John Windmuller(74) *Attorney, Agent, or Firm* — Kilpatrick Townsend & Stockton LLP(57) **CLAIM**

The ornamental design for a transceiver, as shown and described.

DESCRIPTION

FIG. 1 is a perspective view of a transceiver.

FIG. 2 is another perspective view of the transceiver of FIG. 1.

FIG. 3 is a front view of the transceiver of FIG. 1.

FIG. 4 is a right side view of the transceiver of FIG. 1, the left side view being a mirror image of the right side view; and, FIG. 5 is a top view of the transceiver of FIG. 1, a bottom view being a mirror image of the top view.

The broken lines illustrate boundaries of the claimed design, and form no part of the claimed design.
